F. A. Fickhardt.

Heating Stove.

Patented Apr. 28, 1836.

Apr 28, 1836

Frederick A. Fickhardt. Caston P. W.
Letters Patent.

The Schedule referred to in these Letters Patent, and making part of the same, containing a description in the words of the said Frederick A. Fickhardt himself, of his improvement in coal stoves.

To all to whom these presents shall come.

Be it known that I, Frederick A. Fickhardt, of the Borough of Caston, in the County of Northampton and State of Pennsylvania, have invented certain new and useful improvements in coal stoves, that is to say ordinary coal stoves; and that the following is a full and exact description thereof, to wit:—
1st A plain draught flue extending itself over the outer surface of the stove or cylinder (as the case may be), and in the draft and model accompanying this specification made to extend itself upwards over the hinder face of the stove, having an opening at the end, the upper extremity of the flue, communicating with the apartment to be heated, for the purpose of admitting the draught into the flue; and another at the opposite extremity communicating with a chamber beneath the gate, for the purpose of giving the draught and also a third opening on a horizontal or nearly vertical line with the gate, for communicating with the apartment, for the purpose of giving a draft or air to the stove or cylinder, presently hereinafter to be described; The first and third openings having doors slides herewith, the same being opened or closed at pleasure. 2nd An orifice, i.e., one or more in the body of the stove or cylinder above the grate and within the flue above described in 1st, for the introduction of a poker for the purpose of raising the fire. 3rd A "Gate" called, i.e., on the outside of the stove, to a right-angled bar of the gate for the purpose of raising the gate when down, said gate being the axis of swing and

and dependency to the gate. What I claim as my own invention and not previously known of the above described parts is in the first place the "Flame draught flue" as described in & 1. of the above specifications; and in the second place, the "Orifice above the gate" as described in & 2. of the above specifications and in the third place, the "Lever Handle on the outside of the door", as described in & 3. of the above specifications. 1st. A projecting ledge for directing ashes falling at sides into the receiver. 2d. The design and use of the flue as above described, is to furnish a full draught of hot air, uninpaired in its combustible qualities, as far, no perhaps is practicable, and at the same time to promote a circulation and a change of air within the apartment, by taking its supply of air therefrom, and as well also, to receive any fire, ashes, smoke, dust &c. which may escape out of the orifice described in & 1. d. as above, in closing the fire and otherwise. 3. The design and use of the orifice as above described, is to permit an easier and more effective use of the poker; and to give the person operating on the contents of the stove a cylinder, a place where for the exercise of his power the orifice is placed within the flue in order to prevent any danger from the escape of fire from it or any incumbrance from such ashes, dust, or smoke as may find exit through the same. 4. The design and use of the Lever Handle as described in & 3. is also to enable the person attending to the stove to raise the fallen gate from without, thereby avoiding the disagreeable necessity of entering beneath it in order to elevate it to its ultimate position. 4th. The design of the ledge to admit ashes &c. into the receiver.
